Filed May 5, 1961, Ser. No. 65,038

Term of patent 3½ years

(Cl. D33—14)

FIG. 1

FIG. 2

FIG. 3

FIG. 4

FIG. 1 is a perspective view of a combined table and chair unit, showing my new design;

FIG. 2 is a plan view thereof;

FIG. 3 is a vertical sectional view, taken on the secant line 3—3 of FIG. 2; and

FIG. 4 is an end elevational view of the combined table and chair unit.

The dominant features of my design reside in the outline and configuration of the combined table and chair unit or similar article, which comprises a rectangular topped table which is supported on each of its shorter sides by an extended arm integrally connected thereto and emanating from a chair of the configuration disclosed, all as shown in the drawing.

I claim:

The ornamental design for a combined table and chair unit or similar article, substantially as shown and described.
